(57) **CLAIM**

The ornamental design for an electrical deodorizer, as shown and described.

DESCRIPTION

FIG. 1 is a perspective view of an electrical deodorizer showing my new design;

FIG. 2 is a front elevation view thereof;

FIG. 3 is a rear elevation view thereof;

FIG. 4 is a left side elevational view thereof, a right side elevational view being a mirror image thereof;

FIG. 5 is a top plan view thereof; and,

FIG. 6 is a bottom plan view thereof.

The broken lines showing portions of the electrical deodorizer are included for the purpose of illustrating portions of the article and form no part of the claimed design.
